UNITED STATES PATENT OFFICE.

JAMES A. DORAN, OF PROVIDENCE, RHODE ISLAND.

PERCUSSION-PLUNGER.

1,287,916.

Specification of Letters Patent. Patented Dec. 17, 1918.

Application filed April 6, 1918. Serial No. 227,021.

To all whom it may concern:

Be it known that I, JAMES A. DORAN, a citizen of the United States, residing at Providence, in the county of Providence and State of Rhode Island, have invented a certain new and useful Improvement in Percussion-Plungers, of which the following is a full, clear, and exact description.

This invention relates to percussion plungers for all types of projectiles, whether used in the nose, as is common in the fuse of a shrapnel shell, or in the base, as in high explosive shells.

The main object of the invention is to provide a plunger which will render the shell proof against accidental explosion, and also insure explosion on impact after it is fired from the gun and reaches its destination. Various plungers which have been designed for this purpose are not wholly reliable. Some fail to give the safe protection that is so highly important, and others fail to cause an explosion on impact.

Another object is to produce a percussion plunger almost entirely by the simplest of machine operations, namely, turning and drilling, thus reducing the cost of manufacture, and permitting production in large quantities in relatively short time without necessitating the installation of special machinery.

The invention consists in a percussion plunger provided with a central bore to which is loosely fitted a tapered firing pin adapted to be forced into the bore to thereby assume a fixed armed position by frictional engagement when the shell containing the plunger is projected or fired from the gun or other projecting means, as I will proceed now to explain and finally claim.

In the accompanying drawings illustrating the invention, in the several figures of which like parts are similarly designated, Figure 1 is a longitudinal section of a fuse block such as is used in detonators of high-explosive shells provided with the plunger of the invention and showing the plunger in unarmed position. Fig. 2 is a view similar to Fig. 1 but showing the plunger in armed position and advanced into position for firing the fulminate cap or primer. Fig. 3 is a perspective view of the plunger and its parts disassembled. Fig. 4 is a fragmentary sectional elevation showing the method of

retaining the shearable pin in place. Fig. 5 is a fragmentary sectional elevation showing the plunger applied to a combination timing and percussion fuse. Figs. 6 and 7 are, respectively, a longitudinal section and a sectional elevation illustrating modifications in which the plunger and a restraining spring are assembled as a unit for ready application to a fuse block.

The invention may in practice assume various specific embodiments to suit special conditions and types of shells, but for purposes of illustration of the principle of the invention, I have shown a plunger 1 having a central tapered bore 2. Fitted loosely to this bore is a complementally tapered firing pin 3. The firing pin is retained in normal, unarmed position by means of a transverse shearable locking pin 4 passing through a hole in it and through a hole in the plunger 1 and having the edges around the hole turned or peened in as at 5, so that the pin will always remain fixed in the plunger, as shown most clearly in Fig. 4. This firing pin has the firing point 6, and the pin 4 holds the firing pin in such relation to the plunger that its firing point 6 is flush with or slightly back of the forward end of the plunger. The pin 4 is of such diameter that the projective force or "set" of the gun will cause the plunger 1 to shear it and drive the firing pin 3 into the plunger, as shown in Fig. 2, the tapers making a very firm hold between firing pin and plunger, but it is not of a diameter so small that accident, such as dropping of the shell during loading or transportation, will shear it.

The plunger 1 is provided with one or more vents 7 to permit air to pass from one end to the other as it slides in the chamber of the fuse block, thus precluding the possibility of the formation of an air-cushion or a vacuum at either end of the plunger to interfere with its proper operation. If desired, however, the vents may be omitted as in Fig. 2, in which case the plunger would be made to so fit the chamber as to allow air to escape between it and the wall of the chamber of the fuse block.

In order to guard against premature explosion of the shell which might be caused by advancing of the plunger in armed position due to decreased momentum of the shell in transit, a spiral or other suitable spring

8 is interposed between a shoulder 9 on the plunger and the end of the chamber in the fuse block, but this spring is not sufficiently stiff to unduly retard the advancement of the plunger as desired upon impact.

For convenience in installing these plungers in the chambers of fuse blocks, I may make the plunger 1 and spring 8 as a unit, by assembling the two within a sleeve or casing 10 adapted to fit the chamber of the fuse block. Two forms which this sleeve or casing 10 may take, among others, are shown in Figs. 6 and 7, in the former the sleeve or casing being closed at the rear end 15 as at 11, and in the latter being opened as at 12 and having an inturned annular lip 13 closely fitting a shouldered recess 14 at the end of the plunger 1.

In operation, the plunger is assembled in 20 the chamber of the fuse block as described, the spring 8 holding it with the rearwardly projecting end of the firing pin 3 in contact with the rear wall 15 of the chamber of the fuse block, as shown in Fig. 1. When the 25 shell containing the fuse block and plunger is fired, the "set of the gun", or projective force exerted upon the shell, forces the plunger rearwardly and shears the pin 4 and drives the corresponding tapers of the 30 bore of the plunger and of the firing pin together with such force as to make their separation practically impossible for all intended purposes. The spring 8 then holds the plunger in its rearmost position during 35 transit of the shell, but when the shell strikes its objective the impact advances the plunger so that the point 6 of the firing pin 3 explodes the cap 16 and hence the explosive charge of the shell. There is no danger 40 of the force of impact releasing the grip of the tapers of the bore and firing pin for the reason that the force exerted by the "set of the gun" is far in excess of the blow required to explode the primer when the shell strikes 45 its objective.

As shown in Fig. 5, the plunger is adapted for use in a combination timer and percussion fuse such as is used on shrapnel shells, and operates in a chamber 17 therein in the 50 same manner as above described with respect to its operation in the fuse block.

As shown in Fig. 6, the bore 2 may be tapered for about three-quarters of its length only, as at 18, the remainder thereof 55 being cylindrical as at 19, and the firing pin 3 provided with a complementally tapered portion 20 and cylindrical portion 21, the cylindrical portions 20 and 21 fitting with an easy sliding fit so as to give a directive 60 bearing to the firing pin. After the pin is sheared, the peened over portion 5 at each end thereof prevents the severed pin ends from working outwardly.

It will be obvious that when the plunger 65 used is of the unit type shown in Figs. 6

and 7, the sleeve or casing 10 entirely fills the chamber of the block or fuse, and the plunger slides within the sleeve or casing.

The plunger of the present invention has advantages over others in that it functions 70 positively, because it depends on two absolutely reliable mechanical operations, viz., shearing of a pin, and locking of tapers. Its arming is not governed by springs, which cause uncertainties in other plungers. It is 75 free from a multiplicity of moving parts, which is common in other plungers, and which gives several chances of failure. By reducing the number of parts, I also greatly 80 reduce expense of manufacture and also increase production.

The simplicity of the plunger permits of accurate mechanical inspection, thus obviating the necessity for expensive time-consuming tests.

The transverse pin precludes accidental 85 explosion of the shell, as only its intentional projection can shear this pin and place the firing pin in armed position. I prefer to use copper as the material from which to 90 make this pin because of its durable, non-corrosive quality.

As already stated, the plunger of the invention may assume various forms to adapt 95 it for the special type of shell and fuse block or fuse with which it is used, and I do not therefore wish it to be understood that I consider the invention to be limited to the specific embodiment herein shown and described, as various changes may be made 100 without departing from the spirit of the invention or the scope of the claims following.

What I claim is:—

1. A percussion plunger, having a tapered bore and provided with a tapered firing pin adapted to be retained in armed position by frictional engagement therewith.

2. A percussion plunger, provided with a tapered central bore, and a tapered firing pin fitted in said bore and adapted to have a limited longitudinal movement therein whereby frictional engagement is obtained to hold said pin in armed position.

3. A percussion plunger, adapted to have a longitudinal sliding movement within the chamber of an ammunition fuse, said plunger provided with a tapered central bore, a tapered firing pin fitted loosely in said bore and held in unarmed position therein by a transverse pin and adapted upon the shearing of said pin by projective force to assume a fixed armed position by frictional engagement with said bore.

4. A percussion plunger, provided with a tapered central bore, a tapered firing pin held by a transverse shearable pin in unarmed position in said plunger, said transverse pin adapted to be sheared by projective force to allow said firing pin to assume a fixed armed

position by means of the wedge action of the coacting tapers of said bore and firing pin.

5. A percussion plunger, provided with a tapered central bore, a correspondingly tapered firing pin fitted to said bore and adapted to be retained therein in armed position by frictional engagement with the interior surface thereof, and a vent opening extending through said plunger.

10. 6. A percussion plunger, provided with a central longitudinal bore, a firing pin fitted to said bore, said plunger and firing pin being provided with registering transverse holes and a pin passing through said holes, the outer extremities of the hole in said plunger being turned or peened over upon the pin ends.

15. 7. A percussion plunger, provided with a central longitudinal bore, a firing pin fitted to said bore, said plunger and firing pin be-

ing provided with registering transverse holes, and a pin passing through said registering transverse holes and adapted to be sheared by the coaction of the plunger and firing pin in the act of firing and its severed 25 parts held from withdrawal by peening or turning over the metal of the plunger upon its ends.

8. A percussion plunger, a restraining spring therefor, and a casing fitted to said 30 plunger and adapted to engage said spring to hold the same in operative relation to said plunger to thereby form an operative unit.

In testimony whereof I have hereunto set my hand this 1st day of April A. D. 1918. 35

JAMES A. DORAN.
